UNITED STATES PATENT OFFICE.

FREDERICK HYMANS, OF SHALER TOWNSHIP, ALLEGHENY COUNTY, PENNSYLVANIA,
ASSIGNOR TO OTIS ELEVATOR COMPANY, OF JERSEY CITY, NEW JERSEY, A CORPO-
RATION OF NEW JERSEY.

CONTROLLING DEVICE FOR MOTORS.

1,141,548.

Specification of Letters Patent.

Patented June 1, 1915.

Application filed April 10, 1911. Serial No. 619,956.

To all whom it may concern:

Be it known that I, FREDERICK HYMANS, a subject of the Queen of Holland, and resident of Shaler township, in the county of 5 Allegheny and State of Pennsylvania, have invented certain new and useful Improvements in Controlling Devices for Motors, of which the following is a specification.

The invention relates to motor controlling apparatus, and has for its primary objects; the provision of improved means for effecting the acceleration of the motor to full speed automatically and in relation to the load on the motor; the provision of improved means of the character specified that are applicable to both direct and alternating currents; the provision of automatic means for cutting out the starting resistance, so arranged that the device will not operate to 20 cut out the resistance in case of an overload on the motor; and the provision of an arrangement of controlling windings for the cutting out switches, so arranged that such windings will be automatically short circuited when the starting resistance is cut out. Certain embodiments of my invention are shown in the accompanying drawings, wherein:—

Figure 1 is a diagrammatic view showing 30 the application of the invention to a direct current motor, Fig. 2 is a view similar to that of Fig. 1, but with a modified arrangement of switch control, the apparatus being controlled from a master's switch. Fig. 3 is 35 a partial diagrammatic view showing a modified arrangement for securing the release of the cut out switches by means of a connection to the brake operating mechanism, and Fig. 4 is a diagrammatic view 40 showing the application of the invention to an alternating current motor of the induction type.

In Fig. 1 the invention is illustrated as applied to a direct current shunt motor in 45 connection with a manually operated main switch. In this figure 1, and 2 are the positive and negative mains, 3 is the armature, 4 is the shunt field, 5 and 6 are portions of the starting resistance designed to be successively cut out as the motor speeds up, 7 is a manually operated main switch provided with the contact member or brush 8, and 9 is a contact segment with which the contact member is adapted to engage when

the switch is moved from open to closed 55 position.

Integral with the switch arm is a pinion segment 10 designed to intermesh with a vertical rack 11, suitably guided, and having a rest 12 beneath the plate 13 carried by the end of the rack. 14 and 15 are the windings of what may be termed the accelerating magnets, of which there are two as illustrated, but which may be used in any desired number, depending upon the number of steps in which the starting resistance is to be cut out. Working through the windings 14 and 15 are the solenoid rods 14' and 15', which rods are pivoted at their lower ends to the switch arms 16 and 17, 70 such switch arms carrying at their outer ends the contact members 21 and 20, and at their inner ends the set screws 18 and 19 with which the plate 13 is adapted to engage. The weight of the rack 11 and the 75 plate 13 bearing against the set screws 18 and 19 normally holds the switch arms 16 and 17 with their contacts 21 and 20 in the position shown, but when the plate 13 is raised, the switch arms tend to swing by 80 gravity downward so that the contact members 20 and 21 engage respectively with the contact members 23 and 22. The windings 14 and 15 are connected in parallel with the starting resistance 5 and 6 by means of the 85 wire 27, and are energized by reason of the difference in potential between the points 24 and 25 of the resistance. When the switch arm 17 is in closed position with the contact 20 upon the contact 23, the portion 90 5 of the starting resistance is short circuited by reason of the connections 28, 29 and 30, and when the contact member 21 is against the contact member 22, the entire starting resistance 5—6 is short circuited by 95 the connections 28, 31 and 32.

The operation of the apparatus is as follows, starting with the motor at rest, and the parts in the position shown in Fig. 1. The main switch arm 7 is moved in the direction of the arrow until the part 8 makes contact with the segment 9 of the switch, at which time the current from the main 1 flows through the motor including the field and starting resistance in the usual manner. 105 The motor now receives the maximum current, and the current passing over the starting resistance will cause a potential differ-

ence to occur between its terminals 24 and 25. The windings 14 and 15 will therefore become energized, and are of sufficient strength to hold the switch arms 16 and 17 in the position shown, even after the holding plate 13 is raised, the winding 14 being of greater strength than the winding 15. A further movement of the switch arm 7 in the direction of the arrow will cause the engagement of the pinion segment 10 with the rack 11, the rack being moved upward and thus carrying the holding plate 13 away from the set screws 18 and 19. At this time the switches 16 and 17 are held in the position shown by reason of the action of the current in the windings 14 and 15 upon the solenoid bars 14' and 15', the windings being of sufficient strength to maintain the switch arms in raised position as long as the maximum current flows through the armature, that is, when the greatest potential difference between the terminals of the starting resistance 24, 25 occurs, so that the switch arms remain in their uppermost positions in case the motor should stall under an over-load. If however, the motor speeds up, the counter-electro motive force generated by the rotation of the motor will reduce the current that the armature receives. Consequently less current will pass over the starting resistance, with a corresponding decrease of the potential difference between the points 24 and 25. The windings 14 and 15 thus receive less current, and their magnetic pull decreases. As the motor continues to gain speed, the magnetic pull of the windings decreases more and more, until finally a point is reached where the winding 15, being made initially with the weakest magnetic pull, drops its switch arm 17, permitting the contact 20 to engage the contact 23, and thereby short circuiting the portion 5 of the starting resistance, the current passing from the point 26 through the connections 30, 29 and 28 to the armature. The cutting out of the portion 5 of the starting resistance will cause a new increase of current with a new accelerating impulse on the motor, with the stronger winding 14 still receiving sufficient current to maintain the switch arm 16 in open position. With the further acceleration of the motor, however, this second inrush of current gradually reduces to normal, with a corresponding reduction of the potential difference between the points 25 and 26 of the starting resistance, and of the magnetic pull of the magnet. When the armature current is again nearly normal, the magnet 14, being adjusted correspondingly, will no longer be able to hold the switch arm 16 in upper position, and it will therefore drop, making the contact between the parts 21 and 22, and thereby short circuiting the entire starting resistance 5-6, the current passing through the

connections 32, 31, and 28 to the armature after which the motor accelerates to full speed.

In the arrangement shown in Fig. 1, the windings 14 and 15 are shown as connected in series to the terminals 24 and 25 of the starting resistance, but from the foregoing operation it will be clear that the windings may be connected in other ways, the result being the same, if each winding is connected in parallel to the points 24 and 25, or in series or in parallel to any other points of the starting resistance, the only requirement being that these windings shall be subjected to a potential which diminishes as the motor increases in speed. It will also be seen that with the arrangement as shown in Fig. 1, the windings 14 and 15 receive no current when all of the starting resistance is cut out, as these windings are short circuited simultaneously with the short circuiting of the starting resistance. They therefore receive current only a short period, and their air gaps can be arranged to be very small, all of which tend to permit the use of small inexpensive magnets. It will be understood that Fig. 1 is merely illustrative of the invention, and that the construction of the main switch, the means for releasing the switch arms, and the manner of connecting the windings are capable of much variation.

In Fig. 2 are shown substantially the same arrangements as in Fig. 1, with the exception that the switch controlling mechanism is different, a master switch being employed instead of the direct acting switch 7 in Fig. 1. In this arrangement the solenoid bar 33 is employed instead of the rack bar 11, such bar being controlled by means of the winding 34. 35 is the master switch which is adapted to have its contacts 36 and 37 successively engage its segments 38 and 39. 40 is still another switch having a contact 41 adapted to engage a contact 42 when the switch is closed, the switch being operated by means of a winding 43 operating the solenoid bar 44. Starting with the parts in the position shown and the motor at rest the operation is as follows. The arm 35 is moved in the direction of the arrow, making the contact between the parts 36 and 38. Current then flows through the winding 43 via the connections 45, 46 and 47 energizing such winding and causing the closure of the switch 40. The closure of this switch completes the main circuit, and causes the starting of the motor in the manner heretofore described in connection with Fig. 1. A further movement of the switch 35 causes the engagement of the contacts 37 and 39, thus permitting current to flow through the winding 34 via the connections 48 and 49, thus energizing this winding and causing the lifting of the solenoid 33, thus releasing

the set screws 18 and 19, after which the operation of the device is precisely the same as heretofore described in connection with Fig. 1.

5 In Fig. 3 I have illustrated still another manner in which the release of the additional holding means for the switch arms for cutting out the starting resistance may be controlled. This is accomplished in this 10 case by utilizing the brake which is ordinarily used in connection with a motor of this class for securing the release. As shown in this figure, 50 is the drum, 51, 52, are the brake arms normally held in braking position by means of the spring 53, 54 and 55 are solenoid plungers carried by the brake arms 51 and 52 respectively and working in the winding 56, and 57 is a connecting arm between the brake arm 51, and a holding member 13', which holding member corresponds to the plate 13 in Figs. 1 and 2, and engages the set screw 18 of the switch arm 17, corresponding in all respects to the same parts in Figs. 1 and 2. It will be seen that when 20 current is supplied to the solenoid winding 56 to release the brake arms 51 and 52 from the drum 50, such movement causes the lifting of the member 13' and thus leaves the switch arm 17 to operate in the manner here- 25 tofore described in connection with the operation of the device shown in Figs. 1 and 2. The member 13' is shown as engaging only the set screw of a single switch arm, but it will be understood that this member 30 13' may engage simultaneously any number of set screws carried by a plurality of switch arms, each designed to cut out a portion of the starting resistance.

The invention is also readily applicable to 40 alternating current of which Fig. 4 is an illustration as applied to a three phase induction motor with the starting resistance in the rotor or secondary circuit, in connection with a main circuit closed by a manually 45 operated main switch. In this diagram 7' is the main switch arm having thereon the brushes or contact members 58, 59 and 60 adapted to contact with the segments 61, 62 and 63, and supplied with three phase 50 current from the mains 64, 65 and 66, the segments 61, 62 and 63 being connected with the three terminals 67, 68 and 69 of the stator. 70, 71 and 72 are the three slip 55 rings of the rotor connected to a starting resistance 73 to 75, 76 to 78, and 79 to 81, which resistance may be arranged in any desired form of connection, star, delta or otherwise. 14 and 15 are windings for controlling the operation of the switch arms 60 16' and 17', such arms 16' and 17' being provided on their ends with metal contact members 82 and 83 adapted to connect the contact terminals 84, 85 and 86, and 87, 88 and 89, which terminals are connected to the 65 slip rings and to the starting resistance by

means of the connections 90, 91, 92, 93, 94 and 95 in the manner illustrated in the diagram. It will be seen that when the switch arm 16' is down with the member 82 contacting with the contacts 84, 85 and 86, the 70 portions 74 to 75, 77 to 78, and 80 to 81 of the resistance are cut out, and that when the switch arm 17' is in closed position with the member 83 contacting with the contacts 87, 88 and 89, all of the resistance is cut out of 75 the secondary circuit. The winding 14 is weaker than the winding 15, so that the resistance is cut out in two stages in the manner heretofore described in connection with Fig. 1, but it will be understood that this 80 arrangement is merely illustrative, and that the arrangement may be modified to provide for the cutting out of the resistance in any desired number of steps or stages.

Having thus described my invention and 85 illustrated its use, what I claim is new and desire to secure by Letters Patent is the following:

1. In combination, a motor, a source of 90 electric supply, a main switch arm for controlling the motor circuit, a motor starting resistance, a secondary switch for controlling the starting resistance and constructed to close when not acted upon externally and cut out the said starting resistance, an electro 95 magnetic winding in shunt with respect to said resistance and tending to hold the secondary switch open when current is flowing therethrough, releasable means out of contact with the main switch arm adapted to hold the secondary switch open, and means whereby movement of the main switch arm first closes the motor circuit and thereafter engages the releasable means. 100

2. In combination, an alternating current 105 induction motor, a source of electric supply, a main switch arm for controlling the motor circuit, a variable resistance in the secondary circuit of the motor, a secondary switch mechanism arranged to normally close and cut out such resistance, a releasable means out of contact with the main switch arm for holding the switch mechanism against closure, and means whereby movement of the main switch arm first closes the motor circuit and thereafter engages the releasable means. 110

3. In combination, an alternating current 115 induction motor, a source of electric supply, a main switch arm for controlling the motor circuit, a variable resistance in the secondary circuit of the motor, a plurality of secondary switches each arranged to control a portion of the said resistance and each adapted to normally close and cut out a portion of the said resistance, releasable means for holding the switches against closure, an electro magnetic winding for each switch in shunt with the said resistance and each arranged to hold its switch open when 120 125 130

sufficient current is flowing therethrough, the said windings being of different strength so that one portion of the resistance after another is cut out as the speed of the motor 5 increases, and means whereby movement of the main switch arm first closes the motor circuit and thereafter engages the releasable means.

4. In combination, an alternating current 10 induction motor, a source of electric supply, a main switch arm for controlling the motor circuit, a variable resistance in the secondary circuit of the motor, a secondary switch arranged to normally close and cut 15 out a portion of such resistance, a releasable means out of contact with the main switch arm for holding the switch against closure, and means whereby movement of the main switch arm first closes the motor circuit and 20 thereafter engages the releasable means.

5. In combination, an alternating current induction motor, a source of electrical sup-

ply, a main switch arm for controlling the motor circuit, a variable resistance in the secondary circuit of the motor, a secondary switch arranged to normally close and cut 25 out a portion of such resistance, an electro magnetic winding in shunt with respect to the said resistance and tending to hold the switch open when current is flowing there- 30 through, releasable means out of contact with the main switch arm adapted to hold the secondary switch open, and means whereby movement of the main switch arm first closes the motor circuit and thereafter 35 engages the releasable means.

In testimony whereof I have hereunto signed my name in the presence of the two subscribed witnesses.

F. HYMANS.
